OPHTHALMIC MOUNTING

Charles W. Johnson, South Attleboro, Mass., assignor to Sadler Bros. Inc., a corporation of Massachusetts

Application November 28, 1934, Serial No. 755,154
Renewed May 7, 1937

6 Claims. (Cl. 88—49)

This invention relates to an ophthalmic mounting and pertains more particularly to a mounting for a nose pad; and the invention has for one of its objects the provision of a nose pad which will rock longitudinally of this pad and be prevented from any appreciable lateral rocking movement.

Another object of the invention is the provision of a construction for mounting the nose pad by which the pad may be readily detached from its supporting arm and the pad repaired or another pad substituted therefor.

Another object of the invention is the provision of a means by which the extent of longitudinal rocking movement of the pad can be governed and nicely controlled.

Another object of the invention is the provision of a suitable shaping of the supporting arm so as to provide a smooth rocking and fitting of the arm and pad.

A further object of the invention is the shaping of the gold plated parts so that the minimum amount of base metal beneath the plating will be exposed so as to reduce the area in which corrosion may take place.

A still further object of the invention is the simplification of the construction, whereby the manufacturing costs are reduced to the minimum.

With these and other objects in view, the invention consists of certain novel features of construction, as will be more fully described, and particularly pointed out in the appended claims.

In the accompanying drawing:

Fig. 1 is a fragmental perspective view of a portion of an ophthalmic mounting, showing a nose pad in the position which it assumes in relation to the rim and bridge.

Fig. 2 is a plan view of the nose pad and supporting arm attached thereto.

Fig. 3 is a sectional view on line 3—3 of Fig. 2.

Fig. 4 is a side elevation of the nose pad and arm illustrating in full lines one relative position of these parts and in dotted lines another position of these parts.

Fig. 5 is a side elevation of the pad and tongue partially bent.

Fig. 6 is a perspective view of the arm.

Figs. 7, 8 and 9 are top plan views of varying forms of arms showing different modifications of arrangements of the openings and recesses therein.

Fig. 10 is a sectional view thru the arm and pad, the arm being of the type shown in Fig. 7.

Fig. 11 is a sectional view similar to Fig. 10, showing the arm as illustrated in Fig. 8.

Fig. 12 is a sectional view similar to Fig. 10, showing the arm as illustrated in Fig. 9 and a different form of tongue.

Fig. 13 is a sectional view thru a modified form of pad tongue.

Fig. 14 is a plan view of Fig. 13.

Fig. 15 is a plan view of a pad showing the arm mounted in a direction different from that shown in the remaining figures.

Fig. 16 is a sectional view on line 16—16 of Fig. 15.

Fig. 17 is a sectional view of a modified form of bending of the tongue of the pad.

Fig. 18 is a section of the arm showing the plate covering the stock.

In the use of nose pads for ophthalmic mountings, it is desirable that some rocking motion be permitted in order that the nose pad may adjust itself to the face of the wearer. Such rocking motion as occurs should occur longitudinally of this nose pad rather than laterally thereof and thus it is desired to limit the lateral movement of the pad. Further, in the customary mounting corrosion exists to a considerable extent between the post or stud extending from the rear of the pad and the opening thru the arm, which opening is pierced to expose some base metal not protected by the outer gold or other precious metal plating. This corrosion frequently occurs to such an extent that the pad may rotate about its stud as a center and should such a condition occur, it is desirable to take off the pad and replace it with a new one which will be restricted in its movements as desired. And in order that these undesirable conditions may be prevented and the movement governed in the desired manner and also that the pad may be easily interchangeable, I have reduced the exposure of base metal by providing a bendable plated tongue on the pad which may extend thru an opening in the supporting arm and there be bent into a recess to retain it in position. This recess is adjacent to the opening thru which the tongue extends so that the tongue may lodge therein and assist in preventing lateral rocking of the pad. This tongue also provides a means due to the bending thereof by which the extent of rocking may be governed and nicely controlled; and the following is a more detailed description of the present embodiment of this invention illustrating the preferred means by which these advantageous results may be accomplished:

With reference to the drawing, 20 designates

- 5 a lens rim having a bridge 21 secured thereto and a pad-mounting arm 22 connected at the junction of the bridge and the rim. This pad arm has mounted thereon a nose pad 23 which consists usually of celluloid or like material 24 molded or in some manner suitably secured about a sheet-metal plate 25 serving as a core for the pad. A tongue 26 of gold plated wire is suitably secured to this core 25 and extends from the rear surface of the pad.
- 10 The arm designated generally 22 is of plated stock and provided with a spoon-shaped end 27 having a longitudinal slot or recess 28 pressed therein. At one point along this recess an opening 29 is provided extending thru this spoon-shaped end 27 of the arm and thru this opening 29 the tongue extends and is bent as at 30 so that its end 31 extends into the recess 28 and assists in preventing the rocking or turning of the 15 pad about the tongue as a center.
- 15 The tongue 26 is of a width considerably greater than its thickness and the opening 29 is of a corresponding shape so that rotation about the tongue as a center would be prevented.
- 20 However, with the end of the tongue extending into and closely fitting the recess 28 and contacting with the recess at a point distant from the opening lateral rocking is prevented altho longitudinal rocking is permitted, which is highly desirable. In order to govern the amount of 25 longitudinal rocking between the pad and its arm, I nick the arm as at 32 to determine the point of bending, or this may occur by partially bending the tongue at a point spaced from the back 30 of the pad, in order that the desired rocking movement may occur. In use, the end 31 of the tongue will be bent down rather tightly against the spoon-shaped end of the arm so that this end will serve as a pivot point and there will be longitudinal play or rocking movement determined by the extent of the portion extending 35 perpendicularly from the back of the pad and between the pad back and the bend at whatever point the bending occurs.
- 40 Another method of governing the amount of longitudinal rock would be to bend the tongue sharply over the edge of the opening 29, as in Fig. 17, at 30, and then allow the free end 31 of the tongue to govern the amount of rock about the opening as a pivot, from the full line position to the dotted line position in Fig. 17. I, however, prefer the former method of governing 45 as will better control the lateral rocking and prevent rotation should corrosion occur.
- 45 In Fig. 13, I have shown a modified form of tongue, which consists of a ribbon of sheet stock bent upon itself as at 35, and then again as at 36 and 37, to provide a core portion 38 to be inserted in the pad. The functioning of the 50 tongue 39 will be the same as the tongue heretofore described. In another instance, a two-part tongue 40 having arms 41, 42 may be secured to a core 43 in pad 44, as shown in Fig. 12, and the two parts passed thru an opening 45 in the 55 arm as shown in Fig. 9, and split and bent in opposite directions into a recess 46 or 47 located on opposite sides of the opening 45.
- 60 Other modifications may consist of providing an arm having a spoon-shaped end 48 with an opening 49 and a notch in its end 50 for the reception of an end 51 of the tongue bent as 65 illustrated in Fig. 10. In another instance, the spoon-shaped end 52 is provided with openings 53 and 54 for the reception of a tongue passed

up thru one opening and into the other opening, as illustrated in Fig. 11.

A still further modification of the construction may consist in so providing the opening that the arm and pad will be at right angles to each other, such for instance as shown in Fig. 15 and in section in Fig. 16. In this case, an opening is provided for the reception of a tongue 55 and a notch 56, also for the reception of the end of the tongue which is led thru the opening and back as at 57 into the notch 56, as clearly shown in Fig. 15.

By this manner of formation, the tongue which is of bendable metal may be passed thru an opening and bent to retain it therein while the 15 tongue is permitted a certain rocking movement and limited in its rotation or lateral rocking movement. Should the pad need changing this tongue may be readily straightened up and passed back thru the opening thru which it extends to 20 readily detach the pad from its mounted position and a new pad substituted therefor.

In forming the arm which is of plated material, the tools will be so formed as to draw the gold plated material over the end of the arm, as shown 25 in Fig. 18 at 61, and this will also take place in cutting off the tongue. In other words, there is a pinching operation rather than a cutting operation in the formation of this plated stock. The only portion of the stock of the mounting, 30 which is not covered by plate is the edge of the opening or hole 29 and this has the gold tongue contacting therewith, which serves to reduce corrosion.

The foregoing description is directed solely to- 35 wards the construction illustrated, but I desire it to be understood that I reserve the privilege of resorting to all the mechanical changes to which the device is susceptible, the invention being de- 40 fined and limited only by the terms of the ap- pended claims.

I claim:

1. In an ophthalmic mounting, a nose pad, a pad-supporting arm, a single tongue provided on said pad and said arm provided with an opening 45 thru which said tongue extends, the tip of said tongue being bent into engagement with the arm at a point spaced a short distance from said opening to determine a pivotal point and the portion of said tongue adjacent the anchored end 50 of the tongue being so shaped as to permit movement of the arm therealong.

2. In an ophthalmic mounting, a nose pad, a tongue extending from the rear face thereof, an arm having a generally vertical end with an opening 55 therein thru which said tongue extends, a recess extending longitudinally of the end portion of said arm from said opening and the tip of said tongue being bent into said recess at a point spaced from said opening to contact said arm. 60

3. In an ophthalmic mounting, a nose pad having a bendable tongue extending from the rear surface thereof, an arm having an opening thru which the tongue extends, and means on the tongue to determine a definite point of bending of 65 said tongue at a point spaced from said pad a distance greater than the thickness of said arm at the point where said opening occurs.

4. In an ophthalmic mounting, a nose pad, a pad-supporting arm, a single tongue provided on 70 said pad, and said arm provided with an opening thru which said tongue extends, said tongue being bent to engage said arm at one location to determine a pivotal point and extending from said pivotal point at an angle to said pad for 75

rocking of said pad about said pivotal point with reference to said arm.

5. In an ophthalmic mounting, a complete nose pad, an arm, a tongue of a single thickness of metal provided on said pad and materially more bendable than said pad or arm and said arm being provided with an opening through which said tongue extends, said tongue being bendable for attachment or detachment of the entire nose pad to or from said arm, said tongue and opening being correspondingly shaped and each having a width greater than its thickness to permit rocking of the parts in a direction longitudinally of the pad, and to prevent the same from rocking in a direction laterally of the pad.

10 6. In an ophthalmic mounting, a complete nose

pad, a pair of parts comprising an arm and a tongue, said tongue being materially more bendable than said pad or arm and adapted to be bent readily in a direction longitudinally of the pad and fixed to one of said parts, the other of said parts being provided with an opening through which said tongue extends, said tongue being bendable for attachment or detachment of the entire nose pad to or from said arm, said tongue and opening being correspondingly shaped and 10 each having a width greater than its thickness to permit rocking of the parts in a direction longitudinally of the pad and to prevent the parts from rocking in a direction laterally of the pad.
